UNITED STATES PATENT OFFICE

LYMAN C. HUFF, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

RETURN BEND FITTING

Original application filed June 19, 1925, Serial No. 38,295. Divided and this application filed June 24, 1929. Serial No. 373,395.

This application is a continuation of my former application Serial No. 38,295 filed June 19th, 1925.

This invention relates to a return bend fitting and refers more particularly to a removable cap placed in the header of the return bend fitting closing the ends of continuous tubes or conduits.

In the specific embodiment of the present invention, the removable cap is held in place in the header by means of a holding lever pivotally mounted with relation to a cross arm, the contacting end of which lever may take the form of an eccentric, which is adapted to contact the exposed surface of the cap and by manipulation of the holding lever to form a wedge fit against the cap when force is applied on the handle of said lever.

This type of return bend fitting is particularly adapted for tubes or conduits for use in the treatment of hydrocarbon oil under a high heat and pressure where it is necessary to remove the closure caps periodically for cleaning of the tubes or for replacement of the tubes.

In the drawings, Fig. 1 is a diagrammatic side elevational view showing one application of my invention.

Fig. 2 is an end view of the return bend.

Fig. 3 is a cross sectional view taken on line 3—3 of Fig. 2.

Fig. 4 is a cross sectional view taken on line 4—4 of Fig. 3.

Fig. 5 is a cross sectional view similar to Fig. 3 showing another form of cap construction.

Referring now in detail to the drawings and particularly Figs. 1 to 4, a conduit or pipe 1 having screw thread 2 is swedged into the header 3. This header 3 is of the usual type having inlet and outlet and communicating passageway 4. The ends of the inlet and discharge sides of the header 3 are normally open, and in this instance are provided with projections 5. These projections are internally recessed or slotted intermediate their length, as shown at 6, for the purpose of receiving the ends of the cross bar or member 7. This cross bar 7 is itself inter-

riorally slotted or apertured, as shown at 8 (Fig. 4) in a lengthwise direction, and the cross member is also preferably thickened in its width intermediate its length, as shown. Transversely of its width and on both sides of the central longitudinal opening 8, the cross arm 7 is provided with the cutaway portions 9. These cutaway portions 9 are adapted to accommodate the projecting ends 10 of the end 11 of the lever 12. The end 11 is mounted on the pin 13 extending transversely of the width of the cross member 7, which pin 13 forms the pivot upon which the end 11 of the lever 12 is movable.

As shown, in the drawings, the end 11 of the lever 12 is preferably constructed integrally with the body portion of the lever 12 and may be formed as an eccentric for a purpose to be hereinafter explained. The lever 12 is held in place on the cross bar 7 by means of the pin 13 and end arrangement 10 in sockets 9 as shown. Adjacent the lower end of the cross bar 7 are outwardly extending lugs or shoulders 14, which are adapted to rest on the upper surface of the lower projection 5 on opposite sides of the slot 6 for the purpose of preventing accidental displacement or movement of the cross arm 7 and also preventing the cross arm from dropping off.

Referring now particularly to the construction shown in Fig. 3, the interior of the header is provided with an annular recess 15 larger in diameter than the normal diameter of the header at that point. An annular open ended plugging member 16 having inwardly tapering sides 17 adjacent one end and other inwardly tapering ends 18 adjacent its other end is inserted into the tapered side 19 of the header so that the lower end of said tubular open ended plug is adjacent to the annular recess 15. It has been found in practice that the construction of an annular ring in this manner prevents any fouling of the plug when it is inserted, due to faulty connections or sharp corners between the tapered side 19 and straight side 20 of the pipe.

A closure cap 21 which may be provided with the lug or lugs 22 and having an inter-

nal tapered seat 23' is adapted to be placed over the open ended plug 16 on the tapered surface 18 thereof. The crown of this plug may have a case hardened insert 23 placed on the exterior thereof to provide a hardened surface against which the end 11 of the lever 12 is wedged.

Describing now the manner of inserting the plug in place, the lever 12 is pushed upwardly so that a point of less diameter between the pin 13 and periphery of the end 11 is reached. The open ended plugging member 16 may then be inserted into the open end of the header so that the tapered sides 17 seat on the tapered seat 19 of said header. The closure cap 21 is then placed over the open ended plugging member 16, the arrangement being such that the tapered contacting portion 23 of the cap 21 seats on the tapered seat 18 of said open ended plug 16. It will thus be seen that the plug 21 is tapered on its inner face. The cross bar 7 is then adjusted in place and the lever 12 is forced downwardly, bringing the high part of the eccentric into contact with the case hardened insert 23'. Great force is then exerted on the lever 12 to force same further downwardly and form a wedge fit between the eccentric and the cap, thus holding the entire assembly in place.

The particular novelty of providing a separable cap 21 and open ended plugging member 16 is in order to allow for throwing away the plugging member 16 when same has been used and partially scored or chewed up by the cleaning rod thus saving the cap 21, or return fitting 3 which of course, are more expensive items.

In Fig. 5, I have shown what may be termed a standard form of cap, with a curved crown and tapering sides seating on the tapered portion 19 of the header. It is to be particularly noted that I do not wish to in any way limit myself to the use of either of these caps, except as set forth in the appended claims.

It is to be noted that the weight of the lever arm will always hold the eccentric in contact with the cap after it is in place. It may be necessary to tap the cap with a hammer, as the lever is being pulled down, in order to force it into its seat. An extension handle 24 may be provided for the lever 12 if found desirable. The extensions 10 are to a certain extent stub-shafts, which project outwardly from both faces of the end 11. It is understood, of course, that the internal pressure is against the seat, tending to tighten the joints. The cross bar 7 is, of course, detachable.

I have described my invention as being applied to return fittings, but it must be understood that it can be used on junction boxes, terminal boxes, hand holes in tube sheets, headers and the like.

I claim as my invention:

1. A return bend fitting for a tubular oil still comprising a header and plurality of openings in one side of said header adapted to receive the ends of still tubes, a second series of openings in said header, the openings of said second series being diametrically opposed to said first mentioned openings, an annular open ended member having inwardly tapered sides adjacent one end thereof and inwardly tapered sides adjacent the other end thereof inserted into each of said second series of openings, plugs adapted to fit over the tapered sides at one end of each of said open ended annular members, a plurality of pairs of projections carried by said header, each pair of projections being positioned in alignment with one of said series of openings, a removable bar adapted to cooperate with each pair of projections, a cam lever carried by each removable bar said cam levers being adapted to bear against said plugs and clamp the same in position.

2. A return bend fitting for a tubular oil still comprising a header, a plurality of openings in one side of said header adapted to receive the ends of still tubes, a second series of openings in said header, the openings of said second series being diametrically opposed to said first mentioned openings and having inwardly tapering walls, an annular open ended member having inwardly tapering sides adjacent each end thereof inserted into each of said second series of openings in such manner that the tapered wall of the opening and the tapered side at one end of the annular member are in wedging relationship and plugs adapted to fit over the tapered side at the opposite end of each of said open ended annular members.

3. A return bend fitting for a tubular oil still comprising a header, a plurality of openings in one side of said header adapted to receive the ends of still tubes, a second series of openings in said header, the openings of said second series being diametrically opposed to said first mentioned openings and having inwardly tapering walls, an annular open ended member having inwardly tapering sides adjacent each end thereof inserted into each of said second series of openings in such a manner that the tapered wall of the opening and the tapered side at one end of the annular member are in wedging relationship and plugs adapted to fit over the tapered side at the opposite end of each of said open ended annular members, and means including cam levers for locking said plugs in wedging relationship with said annular members.

In testimony whereof I affix my signature.

LYMAN C. HUFF.
